UNITED STATES PATENT OFFICE.

JOSEPH F. MACKIN, OF COLUMBUS, OHIO.

CONTACT-POLE RETRIEVER.

No. 860,681.

Specification of Letters Patent.

Patented July 23, 1907.

Application filed April 6, 1906. Serial No. 310,263.

To all whom it may concern:

Be it known that I, JOSEPH F. MACKIN, a citizen of the United States, residing at Columbus, in the county of Franklin and State of Ohio, have invented certain new and useful Improvements in Contact-Pole Retrievers; and I do hereby declare the following to be a full, clear, and exact description of the invention, such as will enable others skilled in the art to which it appertains to make and use the same.

10 The object of this invention is to provide improved means for the prompt, certain and automatic depression or retrieving of the trolley pole when the trolley leaves the wire.

15 The invention consists in the construction herein- after described and claimed, the invention not being confined to precisely the forms and arrangement of parts shown.

In the accompanying drawings—Figure 1 is a top plan view; Fig. 2 is a side elevation; Fig. 3 is a detail 20 of the main cylinder and piston and piston latching devices, looking at them from the side opposite to that seen in Fig. 2, said parts being in the position where the piston is latched; Fig. 4 is a similar view showing the piston drawn farther out for the purpose of releasing it 25 and resetting the latching device; Fig. 5 is a detail with parts in section of the auxiliary cylinder and piston with connections for controlling the operation of the valve that regulates the admission of the operating fluid to the main cylinder; Fig. 6 is a detail of an electro- 30 magnetic apparatus for controlling the operation of the valve that regulates the admission of the operating fluid to the main cylinder.

In the several views 1 designates the trolley pole, a fragment only of which is shown. The pole is pivoted 35 at 1^a to a revolving stem sleeve 2. Extending horizontally from the stem sleeve is a rod 3 to the outer end of which is bolted a cylinder 4. In the cylinder is a piston 5 the outer end of which is provided with a shoulder 6. The piston 5 is connected with the pole 40 by means of rods 7, said rods having turn buckles 7^a, if desired, to vary the length of the connection between the piston and pole. The connection between the piston and pole is shown to be such that the pole will be depressed by the movement of the piston toward 45 the open end of the cylinder.

50 8 designates a spring between the piston and stem sleeve adapted to yieldingly hold the pole up and the trolley against the trolley wire. Mounted on the side of the cylinder is a valve chamber 9 containing a slide valve 10 having a port 10^a.

55 11 is a pressure supply port into the valve chamber, and on the opposite side of said chamber is a port leading into the end of the main cylinder behind the piston. This port is indicated by dotted lines Fig. 5.

55 Referring more particularly to Fig. 5 the slide valve is provided at its right hand end with a protruding stem

12 on which is a spring 12^a tending to draw the valve so that its port shall align with the ports of the chamber; and at its left hand side the valve is provided with a rod 13 terminating in a link-like loop 13^a. On the exposed end of the piston 5 is a stud 14 that projects into the opening of the link-like loop 13^a. Mounted on the cylinder 4 and above the valve chamber 9 is a small cylinder 15 containing a piston 16. The piston 16 has a stem 16^a that is connected at its outer end with one 60 end of a bell-crank lever 17 that carries at its other end a sliding pin 18 to engage a notch 13^b in the rod 13 of the valve 10. On the stem 16^a is a spring 19 that bears against a small bracket 20 attached to the cylinder 15 and the side of the piston 16 and tends to press said piston inward and hold the pin 18 in engagement with the rod 13, thus preventing the operation of the rod until the piston is actuated. The main cylinder 4 communicates with the small supplemental cylinder 15 through a pipe 15^a connected to both. 75

13^c is a stop to limit by abutment against the valve chamber the movement of the valve to a position where the port 10^a properly establishes communication between the pressure supply and the main cylinder. 80

Pivoted at 21^b upon the upper end of the main cylinder 4 is a latching lever 21 the free end of which is adapted to drop in between the shoulder 6 and the end of the cylinder to latch the piston when the trolley is retrieved. Attached to the outer end of the piston is a rod 22 reaching back over the upper side of the cylinder and parallel to the plane of action of the lever 21. 85 The rod 22 has a lug 22^a at its free end adapted to bear against a small lever 21^a projecting fixedly from the axis of the latching lever 21 and thus raise the latching end of the lever when the pole is given a further pull 90 downward after the automatic retrieving action has been completed, as seen in Fig. 4. When the latching end of the lever has been thus raised a small gravity- rest 23 pivoted on the side of the latching lever drops into position to support said latching lever in raised 95 position when the piston is permitted to return to normal position in the cylinder due to the pressure of the spring 8 that also raises the pole. When the piston returns to normal position in the cylinder a plate 22^b on the rod 22 trips the gravity-rest 23 and resets the 100 piston latch in position to drop into latching position for a fresh retrieving operation. In this position the outer end of the latch rests on the upper edge of the shoulder 6 while the piston moves under it. The latching lever can be held from upward jolting and be 105 given downward pressure at its latching end by means of a spring 24 secured to the cylinder and pressing upward on the opposite end of the lever. The cylinder is provided with a vent or vents 4^a to release the retrieving pressure at approximately the moment the 110 cylinder latch is released to latch the cylinder.

The operation of the mechanism thus far described

is as follows: Let the parts be assumed to be in the position indicated in Fig. 2 and that such position is that when the trolley is running on the trolley wire, then if the trolley runs off the wire the pole will swing upward 5 and push inward the piston of the main cylinder, thereby compressing the air therein. This compression of the air will move the piston 15 outward and lift the pin 18, whereupon the spring 12^a will move the valve 10 to establish communication of the pressure 10 supply with the main cylinder. The pressure thus admitted to the main cylinder pushes the main piston outward and therefore depresses or "retrieves" the pole and to a point where the trolley wheel will be well below the trolley wire. The retrieving action carries the 15 shoulder 6 beyond the end of the latching lever 21 so that said latching lever can drop into position to prevent a return of the piston until this is desired. The retrieving action also brings the stud 14 into engagement with the loop-like end of the valve rod and moves 20 the valve 10 to cut off the pressure supply to the main cylinder but the retrieving action continues, owing to the pressure remaining in the cylinder, until the ports 4^a are reached, when the pin 18 is depressed by the spring 19 into the notch 13^b to latch the valve rod. 25 After the automatic retrieving operation is completed the conductor man pulls, by means of the usual rope, the pole a little farther downward or so that the lug 22^a will draw against the small lever 21^a, thus raising the cylinder latch, after which the spring 8 moves the 30 pole toward the conducting wire. It will be observed that the link-like end 13^a permits play of the stud 14 and piston 5 due to the variations in the height of the same trolley wire, but the pole is adaptable to lines the general average of the height of which varies by adjusting the turn buckles 7^a.

In Fig. 6 I have illustrated how an electro-magnet and armature may be substituted for the supplemental fluid pressure cylinder and piston illustrated in Fig. 5, but I have also illustrated in connection with the electro-magnet and armature arrangement a modification 40 of the devices for latching and releasing the stem of the valve for controlling the admission of the fluid pressure to the main cylinder. In said Fig. 6 the character 25 designates the electro-magnet and 26 the armature. 45 27 designates a rod extending from the armature and connected with a double bell-crank lever 34 that carries two pins 28 and 29. A spring 30 between a shoulder on the rod 27 and a standard 31 fixed on the valve chamber tends to pull the armature away from the magnet 50 and to throw the pin 28 downward, but the magnet when energized overcomes said spring and throws the pin 29 down. The rod of the valve in the electro-magnetic arrangement is provided with two elongated notches or grooves 32 and 33. In the position of the 55 parts shown in Fig. 6 the trolley wheel is in contact with the wire and the magnet is preferably energized by a current shunted from said wire. When the trolley leaves the wire the current in the magnet will be broken and the spring 30 will withdraw the pin 29 from its 60 notch 33 permitting the pressure supply valve to be drawn by its spring into position to admit pressure to the main cylinder and consequently to effect the retrieving of the pole as before described. When the pole is retrieved the stud 14 engages the link-like end of the 65 valve rod and draws the valve to cut off pressure to the

main cylinder the pressure remaining therein exhausting through the vents 4^a as before described. When the pole leaves the wire the magnet is, of course, demagnetized and consequently the spring 30 presses the pin 28 downward and when the valve is sufficiently drawn out the said pin drops into and engages the notch 32, thus latching the valve and preventing it from sliding back to its pressure-admitting position while the trolley wheel is being restored to the wire. Upon the restoration of the trolley wheel to the wire the electro-magnet is again energized, thus depressing the pin 29 into its notch 33 in time to prevent the valve from being thrown into pressure-admitting position but still leaving it prepared to be thrown into such position when the electro-magnet is demagnetized by the escape of the trolley wheel from the wire.

It will be noted that the notch 32 is so located with reference to the notch 33 that the pin 28 can be depressed without engaging it when the valve is to be released for the purpose of admitting pole-retrieving pressure to the main cylinder.

It will also be observed that in both cases the notch or groove in the pressure supply controlling valve stem into which the latching pins are projected should be long enough to permit the downward drawing of the pole after the retrieving action is completed to lift and reset the piston latching lever 21.

What I claim and desire to secure by Letters Patent is:

1. In a contact pole retriever, the combination with the pole, means for raising the pole, a main cylinder and a piston therein connected with the pole, said piston when subjected to fluid pressure adapted to depress the pole, said piston also adapted to generate pressure upon the escape of the pole, means for supplying fluid pressure to the cylinder for depressing the pole, a valve to control said pressure supply, means for controlling the operation of said valve comprising a supplemental cylinder communicating with the main cylinder and a piston in the supplemental cylinder actuated by the fluid pressure generated by the escape of the pole.

2. In a contact pole retriever, the combination with the pole, means for raising the pole, a cylinder and a piston therein connected with the pole, said piston when subjected to fluid pressure adapted to depress the pole, means for supplying fluid pressure to said cylinder, a valve to control said pressure supply, and means tending to move said valve to admit the fluid pressure, a supplemental device actuated by the fluid pressure generated by the aforesaid piston upon the escape of the pole from the wire to release said valve to admit pressure to said cylinder, and means actuated by the pole to cut off the pressure.

3. In a contact pole retriever, the combination with the pole, a cylinder with a piston therein connected with the pole, means for raising the pole, said piston when subjected to fluid pressure adapted to depress the pole, means for supplying fluid pressure to said cylinder, a valve to control the pressure supply, means for actuating the valve to admit the pressure supply, means operated by the pole to move the valve to exclude the supply, a latching device to retain the valve in position to exclude the supply and means actuated by the fluid pressure generated by the escape of the contact from the conducting wire to release said latching device.

4. In a contact pole retriever, the combination with the pole, means for raising the pole, a cylinder with a piston therein connected with the pole, said piston when subjected to fluid pressure adapted to depress the pole, means for supplying fluid pressure to said cylinder, a valve to control the pressure supply, a spring for moving the valve to admit the pressure supply, means operated by the pole to move the valve to exclude the supply, a latching device to retain the valve in position to exclude the supply and

- means actuated by the fluid pressure generated by the escape of the contact from the conducting wire to release said latching device.
5. In a contact pole retriever, the combination with the pole, a cylinder with a piston therein connected with the pole, said piston when subjected to fluid pressure adapted to depress the pole, means for supplying fluid pressure to said cylinder, a valve to control the pressure supply, means tending to move said valve to admit the supply, a latch to hold said valve in position to exclude the supply, and a supplemental cylinder communicating with the main cylinder, a piston in said cylinder, means connecting said cylinder and latch whereby when the contact escapes from the wire the main cylinder is moved to compress the fluid therein and actuate the piston of the supplemental cylinder to release said latch.
6. In a contact pole retriever, the combination with the pole, a cylinder with a piston therein connected with the pole, said piston when subjected to fluid pressure adapted to depress the pole, a spring acting upon the piston and tending to raise the pole, means for supplying fluid pressure to said cylinder, a valve to control the pressure supply, means tending to move the valve to admit the supply, a latch to hold said valve in position to exclude the supply, a supplemental cylinder communicating with the main cylinder, a piston in said cylinder, means connecting said cylinder and latch whereby when the contact escapes from the wire the main cylinder is moved by the aforesaid spring to compress the fluid therein and actuate the piston of the said supplemental cylinder to release the said latch.
7. In a contact pole retriever, the combination with the pole, a cylinder with a piston therein connected with the pole, said piston when subjected to fluid pressure adapted to depress the pole, means for supplying fluid pressure to said cylinder, a valve to control the pressure supply, means tending to move said valve to admit the supply, a latch to hold said valve in position to exclude the supply, a latch to retain said piston after the pole is retrieved and a vent to exhaust the fluid from the cylinder approximately contemporaneously with the latching of the cylinder, and means adapted to release said cylinder latch without releasing the valve controlling the pressure supply.
8. In a contact pole retriever, the combination with the pole, a cylinder with a piston therein connected with the pole, said piston when subjected to fluid pressure adapted to depress the pole, means for supplying fluid pressure to said cylinder, a valve to control the pressure supply, means tending to move said valve to admit the supply, a latch to hold said valve in position to exclude the supply, a latch to retain said piston after the pole is retrieved, means operative by the pole for releasing said last named latch, a vent to exhaust the fluid pressure from the cylinder approximately contemporaneously with the latching of the cylinder, means connecting the pressure supply controlling valve with the pole whereby the retrieving action thereof cuts off the pressure supply, said pole being operative to release the cylinder latch without releasing the pressure supply controlling valve.
9. In a contact pole retriever, the combination with the pole, a main cylinder with a piston therein connected with the pole, said piston when subjected to fluid pressure adapted to depress the pole, means for supplying fluid pressure to said cylinder, a valve to control the pressure supply, means tending to move said valve to admit the supply, a latch to hold said valve in position to exclude the supply, a supplemental cylinder communicating with the main cylinder, a piston in said cylinder, means connecting said cylinder and latch whereby when the contact escapes from the wire the main cylinder is moved to compress the fluid therein and actuate the piston of the supplemental cylinder to release said latch.
10. In a contact pole retriever, the combination with the pole, a cylinder with a piston therein connected with the pole, a spring acting upon the piston said piston when subjected to fluid pressure adapted to depress the pole, means for supplying fluid pressure to said cylinder, a valve to control the pressure supply, means tending to move said valve to admit the supply, means to hold said valve in position to exclude the supply, means actuated by the air pressure in the cylinder due to the action of said spring to raise the valve holding means, means for retaining the piston and pole in retrieved position, means connecting the pressure supply controlling valve and pole whereby the retrieving action of the latter cuts off the pressure supply, said pole being operative to release the means retaining the piston and pole in retrieved position without releasing the pressure supply controlling valve.
11. In a contact pole retriever, the combination of the pole, a fluid pressure cylinder and piston therein operatively connected with the pole, a pressure supply to move the piston in one direction to depress the pole, means to move the piston in the opposite direction to raise the pole and compress fluid in the cylinder, and means actuated by such compressed fluid to admit fluid pressure to said cylinder to depress the pole.
12. In a contact pole retriever, the combination of the pole, a fluid pressure cylinder, and piston therein, a pressure supply therefor, means to raise the pole and move the piston to compress fluid therein, means actuated by such compressed fluid to control the admission of pressure supply to said cylinder, a device to latch the pole in its retrieved position, means whereby the pressure supply is cut off, and means whereby the cylinder is exhausted when the pole is retrieved.
13. In a contact pole retriever, the combination of the pole, a fluid pressure cylinder, and piston therein, a pressure supply therefor, means to raise the pole and move the piston to compress fluid therein, means actuated by such compressed fluid to control the admission of pressure supply to said cylinder, a device to latch the pole in its retrieved position, means whereby the pressure supply is cut off, means whereby the cylinder is exhausted when the pole is retrieved, and means whereby said latch is released upon further depression of the pole after it is retrieved.
